UNITED STATES PATENT OFFICE

WALTER HENRY GROOMBRIDGE, OF DEPTFORD, LONDON, ENGLAND, ASSIGNOR TO
ARTHUR J. DICKINSON LIMITED, OF DEPTFORD, LONDON, ENGLAND, A BRITISH
COMPANY

MANUFACTURE OF INSECTICIDES

No Drawing.

Application filed November 23, 1927. Serial No. 235,393.

This invention relates to improvements in and relating to the manufacture of insecticides and its object is to provide a new and improved method of manufacturing insecticides particularly but not exclusively intended for use in cotton plantations for the purpose of destroying certain insects such for example as the pink boll-worm, or the leaf worm which frequently attack cotton plants 10 in certain districts.

Another object of this invention is to provide a method of obtaining a silicofluoride in relatively concentrated aqueous solution.

A further object is to provide a fluid comprising a silicofluoride in solution suitable 15 for use as an insecticide.

A further object is to obtain a silicofluoride in solution by treating an alkaline silico-fluoride either with or without the addition of extra alkali with a solution of one or more soluble soaps.

Various attempts have been made previously to provide satisfactory insecticides for the purpose stated. Thus for example calcium 25 arsenate has been used, but whilst this substance will destroy the insects, its use is attended with many disadvantages due to its poisonous effect on cattle and human beings. It has also been proposed to use sodium 30 silico-fluoride but owing to this substance being very difficult to dissolve in water it has had to be applied by a dusting process in the solid form and this has been found to be both wasteful and troublesome.

The present invention consists of a method 35 of obtaining a silicofluoride in relatively concentrated aqueous solution, thus providing insecticides in a liquid form, such form for the purpose in view being attended with 40 many advantages.

It has been found that if an alkaline silicofluoride is treated with water in the presence of one or more soluble soaps, preferably alkaline soaps and preferably also in the presence 45 of added free alkali a cloudy solution is obtained. This solution may be in the form of a colloidal solution or suspension and the word "solution" wherever used herein is to be taken to include any colloidal solution or suspension of a relatively permanent nature. Simi-

larly the word "dissolve" wherever used herein is to be taken to mean the preparation of a "solution" as above defined. The above mentioned result may be the consequence of a chemical action having taken place, such a reaction certainly taking place if additional alkali is added to the mixture as will be hereinafter described.

I prefer to utilize ammonium silicofluoride and to mix or treat the same with caustic soda or other suitable alkali, the resulting material being treated with an aqueous solution of one or more alkaline soaps. It is advisable for the process of solution to be carried out at a temperature below 30° C.

Of the several alkaline silicofluorides, I prefer to start with ammonium silicofluorides in any convenient state. Caustic soda or other suitable alkali generally up to a weight not exceeding two-thirds the weight of the silicofluoride employed may if desired be used in addition to the silicofluoride and the mixing operation is preferably carried out at temperatures below 30° C.

I do not desire to be limited to any specific proportions of ingredients but so far as my investigations have proceeded I have found that the relative proportions of soap and silicofluoride may vary within fairly wide limits thus for example from equal quantities by weight of dry soap and silicofluoride to about 5 parts of soap to one part of silicofluoride so that my invention may be better understood the following two specific examples are given.

1. 60 lbs. of soft potash soap having a fatty acid content of 40% are made up to 20 gallons with water. In a separate vessel 20 lbs. of ammonium silicofluoride are dissolved in 15 gallons of water and are treated with a solution of 10 lbs. of caustic soda in 5 gallons of water. The second solution is then gradually added whilst stirring to the first solution, maintaining the temperature meanwhile rather below 30° C., thus obtaining approximately 40 gallons of insecticide.

2. 14 lbs. of ammonium silicofluoride are dissolved in 13 gallons of water and 5 lbs. of caustic soda are added thereto. This mixture is then added to 2½ cwts. of soft potash soap having a fatty acid content of 12.6% and

mixed in the requisite quantity of water, the temperature being as before maintained below 30° C. and the mixture being finally made up to a bulk of 40 gallons of insecticide.

5 In either of the above cases the caustic soda can if desired be replaced by other suitable alkali such for example as soda ash or ammonia and the alkali may as stated, either be added to the fluosilicate or to the soap solution and as mentioned above the use of added alkali is not essential for the purpose of the invention although I have found that better results are obtained by its use.

10 For the purpose of obtaining the best results, it is important for the material which is to exercise insecticidal power to be in the finest possible state of division or solution and whilst I do not desire to be limited by any theoretical explanation of the chemical 15 or physical chemical reaction taking place according to the invention I believe that the excellent results obtained are due to one or more chemical and/or physical chemical reactions which cause the formation of colloidal 20 solutions. Thus for example, it is believed that when ammonium silicofluoride is treated with caustic soda, the following reaction takes place to some extent:—

25 $(\text{NH}_4)_2\text{SiF}_6 + 2\text{NaOH} = \text{Na}_2\text{SiF}_6 + 2\text{NH}_4\text{OH}$
that is to say the first result is the formation of some sodium silicofluoride and free ammonia. The reaction probably proceeds further resulting in the formation of sodium fluoride, 30 ammonium fluoride and silicic acid, according to the equation:—

35 40 The result of these two reactions would be the presence of sodium silicofluoride in a very fine state of division either with or without some unchanged ammonium silicofluoride in solution, together with sodium and ammonium fluoride all being either in solution or in a very fine state of division the maintenance of which condition would be assisted by the colloidal solutions of silicic acid and soap. The fluorides resulting from this decomposition also have insecticidal properties.

45 It should be noted that the term "alkaline" as applied to chemical compounds used herein is intended to mean either one or more compounds either of the alkali metals or one or more ammonium compounds and it should further be noted that the invention is not limited to the use of particular chemical substances which have been given by way of examples nor to specific proportions and details 50 nor to the precise order in which the steps are carried out all of which details can be varied without departing from the scope of the invention.

55 If desired insecticides prepared according to the present invention may of course be

mixed at any convenient stage or used with other suitable substances.

I claim:—

1. In a method of manufacturing colloidal alkali metal silico fluorides suitable of use as insecticides the step of treating ammonium silicofluoride with alkali metal soaps. 70

2. In a method of manufacturing a colloidal alkali metal silico fluoride suitable for use as an insecticide the step of treating ammonium silico fluoride with an alkali metal soap. 75

3. In a method of manufacturing colloidal alkali metal silico fluorides suitable for use as insecticides the step of treating ammonium silico fluoride with alkali metal soaps and a caustic alkali. 80

4. In a method of manufacturing colloidal alkali metal silico fluorides suitable for use as insecticides the step of treating ammonium silico fluoride with alkali metal soaps and a caustic alkali. 85

5. In a method of manufacturing a colloidal alkali metal silico fluoride suitable for use as an insecticide the step of treating ammonium silico fluoride with an alkali metal soap and a caustic alkali. 90

6. In a method of manufacturing a colloidal alkali metal silico fluoride suitable for use as an insecticide the step of treating ammonium silico fluoride with an alkali metal soap and caustic alkalis. 95

7. In a method of manufacturing colloidal alkali metal silico fluorides suitable for use as insecticides the step of treating ammonium silico fluoride with alkali metal soaps at a temperature below 30° C. 100

8. In a method of manufacturing a colloidal alkali metal silico fluoride suitable for use as an insecticide the step of treating ammonium silico fluoride with an alkali metal soap at a temperature below 30° C. 105

9. In a method of manufacturing colloidal alkali metal silico fluorides suitable for use as insecticides the step of treating ammonium silico fluoride with alkali metal soaps and a caustic alkali at a temperature below 30° C. 110

10. In a method of manufacturing colloidal alkali metal silico fluorides suitable for use as insecticides the step of treating ammonium silico fluoride with alkali metal soaps and caustic alkalis at a temperature below 30° C. 115

11. In a method of manufacturing a colloidal alkali metal silico fluoride suitable for use as an insecticide the step of treating ammonium silico fluoride with an alkali metal soap and a caustic alkali at a temperature below 30° C. 120

12. In a method of manufacturing a colloidal alkali metal silico fluoride suitable for use as an insecticide the step of treating ammonium silico fluoride with an alkali metal soap and caustic alkalis at a temperature below 30° C. 125

13. In an insecticide, a colloidal alkali metal silico fluoride in the presence of an ammonium soap in an aqueous medium.
14. In an insecticide, a colloidal alkali metal silico fluoride in the presence of an ammonium soap and an aqueous solution of fluorides.
15. In a method of manufacturing colloidal alkali metal silico fluorides, the steps of adding to 60 parts by weight of soft potash soap having a fatty acid content of 160% in 200 parts of water, a solution of 20 parts of ammonium silico fluoride in 150 parts of water, and treating the product with a solution of 101 parts of caustic soda in 50 parts of water, agitating the reagents during mixing and maintaining the temperature below 30° C.
16. In a method of manufacturing colloidal alkali metal silico fluorides the steps of adding 14 parts by weight of ammonium silico fluorides in a solution of 130 parts and 5 parts of caustic soda to 280 parts of soft potash soap having a fatty acid content of 12.6% in water, maintaining the temperature below 30° C. and making up the resulting product to about 3 times the volume of the ammonium silico fluoride solution, the reagents being agitated during mixing.
- 30 In witness whereof I affix my signature.
